UNITED STATES PATENT OFFICE.

WILLIAM MAIR ROLPH, OF LONDON, ENGLAND.

DESIGN FOR A RADIATOR-CAP ORNAMENT.

61,348.

Specification for Design.

Patented Aug. 8, 1922.

Application filed September 12, 1921. Serial No. 500,231. Term of patent 14 years,

To all whom it may concern:

Be it known that I, WILLIAM MAIR ROLPH, a subject of the King of Great Britain, residing at 66 Piccadilly, London, England, have invented a new, original, and ornamental Design for a Radiator-Cap Ornament, of which the following is a specification, reference being had to the accompanying drawings, forming part thereof.

In the accompanying drawings, Figure 1 is a front view, Figure 2 a back view and Figure 3 an underside view.

I claim:—

The ornamental design for a radiator cap ornament substantially as shown.

Signed at London, England, this second day of September, 1921.

WILLIAM MAIR ROLPH.
